GRINDING MACHINE

Alfred E. Hamilton, Pittsburgh, and Laszlo M. Stempel, Coraopolis, Pa.

Application July 6, 1936, Serial No. 88,952
Renewed August 27, 1938

15 Claims. (Cl. 51—122)

This invention relates to grinding machines particularly suitable for automatically grinding the surfaces and edges of plates, blades or other blanks of elongate form to predetermined shape and contour, and is hereinafter described as employed in the grinding and shaping of knife blades.

One object of our invention is to provide a work holder of such form that blanks can be carried thereby across the face of a grinding element and the blank maintained against shifting and deflection under grinding pressure and wherein mechanical "spring" of the holder is eliminated.

Another object of our invention is to provide means for regulating the rate of travel of a work holder in a direction radially of a grinding element.

Another object of our invention is to provide a grinding machine which is automatic in operation, wherein the operations of feeding, advancing, grinding and discharging the blanks are effected sequentially and in timed relation, but wherein the time required for the grinding operation may be regulated at will and independently of the timed relation of the other operations.

A further object of our invention is to provide means for oscillating the blanks during grinding thereof for grinding the blanks along a curved line and so adjusting the oscillating means that only desired portions of the blanks will be ground on such curved line.

Still another object of our invention is to provide means for so varying the longitudinal position of the blanks relative to the grinding wheel during grinding thereof, that the depth of grinding and consequently the contour of the ground surface may be effected as desired.

In the accompanying drawings Figure 1 is a plan view of the grinding apparatus; Fig. 2 is a side elevational view thereof, partially in section; Fig. 3 is a view taken on the line III—III of Fig. 1; Fig. 4 is a view taken on the line IV—IV of Fig. 2; Fig. 5 is an enlarged view taken on the line V—V of Fig. 1; Fig. 6 is a view taken on the line VI—VI of Fig. 5; Fig. 7 is a plan view of one of the work holders, on an enlarged scale; Fig. 8 is a view taken on line VIII—VIII of Fig. 7; Fig. 9 is a view taken on the line IX—IX of Fig. 7; Fig. 10 is a view taken on the line X—X of Fig. 6; Fig. 11 is an enlarged view taken on the line XI—XI of Fig. 4; Fig. 12 is an enlarged view taken on the line XII—XII of Fig. 5; Fig. 13 is a view taken on the line

XIII—XIII of Fig. 12; Fig. 14 is an enlarged view taken on the line XIV—XIV of Fig. 1; Fig. 15 is a view taken on the line XV—XV of Fig. 14; Fig. 16 is a partial plan view of a portion of the structures of Figs. 14 and 15; Fig. 17 is a view taken on the line XVII—XVII of Fig. 14; Fig. 18 is an enlarged vertical sectional view of certain of the valve members of Fig. 17; Fig. 19 is a view taken on the line XIX—XIX of Fig. 18; Fig. 20 is a view taken on the line XX—XX of Fig. 18; Fig. 21 is a development of the timing cams of the timer structure of Fig. 17; and Fig. 22 is a diagrammatic view showing the timing mechanism and the piping connections leading therefrom to various portions of the apparatus.

The apparatus includes a base 10 upon which is mounted a slide 11 (Figs. 1, 2 and 3). A block 12 is slidably supported on the slide 11 for adjustment transversely of the slide 11. A shaft 13 is supported upon the block 12, with suitable bearings. A grinder head 14 is secured to one end of the shaft 13 and carries a grinding wheel or ring composed of emery or other suitable abrasive material. The other end of the shaft 13 is provided with a pulley 16 which is driven by an electric motor 17, through a pulley 18 and suitable belt devices 19. The motor casing is mounted on the bearing block 12 so that the driving connection just referred to can be maintained properly during adjustments of the block 12 on the slide 11.

The slide 11 is adjustable by means of screws 20 so as to vary the position of the grinding wheel 15 relative to the work carrier, to be hereinafter described, in directions axially of the work carrier. The slide 12 is adjustable to move the grinding wheel toward and from the work carrier to compensate for wear on the face of the grinding wheel. This adjustment is effected by means of a nut 21 which is carried by the slide 12 with which a screw shaft 22 has threaded engagement. The screw shaft is journaled in the slide 11 and carries a worn wheel 23 that meshes with a worm 24. The worm 24 is operated by a hand wheel 25 to effect the adjustment just above referred to. By reason of the worm gear and screw connections just described, very accurate adjustments of the grinding wheel toward and from the face of the work carrier can be effected, and the grinding wheel will remain in such set positions.

The work carrier is mounted upon a shaft 27 which is disposed at right angles to the grinder shaft 13 and is supported at its ends in bearings

- 28 and 29 respectively, that are mounted upon the base 10. The work carrier includes end plates or spiders 30 and 31 which have hub-like portions supported by suitable bearings upon the shaft 5 27. The spiders 30 and 31 are rigidly connected in unitary relation by tie rods 32 arranged in groups of three. The spiders together with the rods 32 constitute a rotatable carrier for the work holders.
- 10 Each group of rods 32 carries a work holder 33. The work holders are supported for sliding movement on the rods 32 and each comprises a casing or housing having three cylindrical bores through which the rods 32 extend (Figs. 6, 8, 9 15 and 11). On each housing 33 a bracket 35 is pivotally connected at 36. The bracket has ears 37 through which screws 37a extend, the screws being threaded into the bosses 38 on the housing 33. Springs 39 are interposed between the heads 20 of the screws and the ears 37 to yieldably urge that end of the bracket 35 toward the housing 33. The bracket has journalled thereon a roller 40 that bears against a pattern rod or guide rod 41 which may be of such form as to control the 25 shape to which an article may be ground, as will be hereinafter explained. The rod 41 extends through the housing 33 and through spiders 30 and 31, and is detachably keyed to the spider 31 by a key 42.
- 30 The housing 33 carries a back-up roller 43 that supports the rod 41 against deflection under grinding pressures. The roller 43 is mounted on an eccentric portion of a shaft 44 which is carried by the housing 33, and this shaft is rotatably 35 adjustable in order to raise and lower the back-up roller relative to the guide rod 41, to compensate for wear and to suit rods of various diameters. The shaft is supported between split bearing members 45, which can be brought into tight clamping engagement with the shaft. 40 Loosening of these clamps will permit rotatable adjustments of the shaft 44.
- 45 The bracket 35 carries a rod 47 upon which a recessed block 48 is mounted for rocking movements (Figs. 5, 8 and 9). Springs 49 and 50 are interposed between the block 48 and the bracket 35, near the ends thereof, in order to yieldably maintain the block in a predetermined position upon the bracket 35. The springs 50 are preferably made somewhat heavier than the springs 49, 50 so that they will offer increased resistance to backward tilting of the block 48 when the work is being moved against the grinding wheel.
- 55 A clamp block or bar 52 is secured to the block 48. The block 52 is suitably recessed in its outer face for the reception of the knife blades or other articles to be ground. The walls of the recesses serve to prevent displacement or sliding of the work on the block 52 through friction of the grinding wheel.
- 60 The knife blade or other work, indicated by the numeral 54, is held upon its seat 52 by a clamp 55. The clamp 55 is pivoted upon the block 48 and is yieldably urged toward the clamping block 52 by springs 56. The clamp is opened and closed 65 by means to be hereinafter described. The recessed block 48 has at one end an extension or arm 57, by means of which the recessed block 48 and the parts carried thereby will be oscillated on the shaft 47, as will be hereinafter described.
- 70 A cylinder 58 is formed in each work holder, and extends axially thereof (Fig. 6). A piston rod 59 extends through each cylinder and into the spiders 30 and 31. A piston 60 is secured to the mid-portion of the piston rod 59, and fits 75 within the cylinder 58. The cylinder is provided

with a packing gland 61 at each end thereof, to prevent leakage of fluid from the ends of the cylinder.

The piston rod 59 is provided with bores extending from each end thereof to the piston 60, ports 62 being provided at the inner ends of these bores so that fluid pressure can be admitted into the cylinder at opposite sides of the piston 60. The work holder can thereby be reciprocated longitudinally of the tie rods 32. 10

With the parts in the positions shown in Fig. 6, the admission of fluid pressure to the right hand end of the piston 60 will cause the work holder to move to the right, carrying with it the work clamping devices above described. The 15 roller 40 will move along the pattern rod 41 and be held in yieldable engagement therewith by the springs 39, as above described, so that the bracket 35 will be oscillated or be gradually tilted in a radial direction relative to the axis of the 20 carrier, and consequently vary its position relative to the grinding wheel, thus varying the depth to which the grinding of the work is effected and consequently the contour of the ground surface, which contour is determined by the shape of the 25 pattern rod 41. As shown more clearly in Fig. 2, there are six work holders mounted upon the rotatable carrier, and each work holder is of the construction above described.

The spider 30 of the carrier has an extended 30 hub to which is secured a ratchet wheel 63 and a locking disc 64 (Figs. 5 and 6). The locking disc has six notches in its periphery—one for each of the work holders. A locking lever 65 is pivotally mounted on the bearing housing 28 and carries 35 a boss or lug 66, which is moved into the notches of the locking disc 64, to hold the carrier against rotation when the work holder is in grinding position.

Step-by-step movement is given to the carrier by means of a pawl 67 which engages the ratchet 40 teeth in the ratchet disc 63. The pawl 67 is pivotally mounted between arms 68 that have circular extensions which are journalled on the hub of the spider 30. The outer ends of the arms 68 are pivotally connected to a piston rod 69 which extends into a cylinder 70. Fluid pressure is alternately admitted to opposite ends of the cylinder 70 through pipes 71 and 72, to effect reciprocation of the piston rod 69, and to actuate the pawl to rotatably advance the carrier with 50 a step-by-step movement. A spring 73 yieldably holds the pawl 67 in working engagement with the ratchet teeth. This spring 73 is carried by one of the arms 68. 55

Since the inner end of the piston rod 69 oscillates on an arc, provision is made to permit the cylinder to oscillate and thereby avoid binding of the piston rod 69. To this end, the cylinder 70 is pivotally connected at 75 to the bracket arms 60 76, which extend from the housing 28.

The locking lever 65 is operated by a piston 77 disposed within a cylinder 78. The piston 77 is carried by a piston rod 79 which extends toward and is opposite to the piston rod 69. The inner end of the piston rod 79 carries a roller 80 which engages the upper end of the locking lever 65 to push the lever into locking engagement with the disc 64, when fluid pressure is admitted to the cylinder 78 through a pipe 81. Air pressure admitted to the cylinder 78 will exert a yieldable 70 force to push the locking lever toward the disc 64, so that when a notch comes opposite to the lug 66, the lever will snap into locked position. Retractive movement of the piston 77 and release of the locking dog 66 will be effected by the pis- 75

ton rod 69 moving toward the left (Fig. 5), so that a roller 82 on the inner end of the piston rod 69 will engage the inner face of the lever 65, thus releasing the lock at 66 automatically when the 5 pawl 67 is being drawn back to engage another notch in the ratchet wheel 63. The upper end of the lever 65 has an extension which engages with a bell crank lever 86 which is pivotally mounted in a housing 87, that is positioned upon 10 the cover plate of the housing 28. The horizontal leg of the bell crank lever engages the stems of valves 88 and 89 which control admission of air through the piston rods 59 to the cylinder 58, as will be hereinafter described.

15 Means are provided for stopping the rotative movement of the carriage at points intermediate where it is locked by the lever 65, to permit of feeding blanks to the work holders. This means is shown more clearly in Figs. 1, 5 and 6, and 20 constitutes a piston rod 90 operating in a cylinder 91 to the opposite ends of which fluid pressure is admitted through pipes 92 and 93, to effect reciprocation of the piston rod. The outer end of the piston rod is movable into the path of the 25 pattern rods 41, the timing relation of the feeding mechanism and the actuation of the locking piston 90 to be hereinafter described.

As shown more clearly in Figs. 1, 2 and 4, the feeding device for supplying the work or blanks 30 to the work holders is mounted upon brackets 100, which extend upwardly from the base 10, and comprises a slide plate housing 101 in which a slide plate 102 is mounted. At its forward edge, the slide plate carries projecting fingers 103 35 which, when the slide plate advances, will engage the lowermost blank 54 of a stack contained within vertical slide or guide ways 104. Forward movement of the slide plate 102 will slide the bottommost blank between the pivoted clamping jaw 55 and the clamp block 52.

40 The clamp block 52 is recessed or grooved, as shown in Fig. 6, to permit the fingers to move sufficiently far that the blank will be properly pushed into the recessed upper face of the clamp block, and beneath the pivoted clamp 55. Reciprocatory movement of the slide plate 102 is effected by means of a piston rod 105 and a cylinder 106, fluid pressure being admitted to the opposite ends of the cylinder through pipes 107 and 108.

50 The operation of the feed slide is, of course, timed relative to the movements of the other parts, as will be later explained.

As shown more clearly in Fig. 2, the work 55 holders as they approach blank receiving position, pass beneath camming blocks 109, with which the rear ends of the pivoted clamp 55 engage to open the clamp for the reception of a blank. The clamping jaws 54 are operated in a somewhat similar manner to open the same at the discharging station, after the blanks have passed the grinding wheel. This opening means is shown in Fig. 2 and consists of a camming block 110 that will be engaged by the tail of each 60 clamp to rock the same and effect release of the ground blank.

65 As heretofore mentioned, each work holder, when in position adjacent to the grinding wheel, is moved along the rods 32 by admission of fluid pressure to its cylinder 58 through the piston rods 59. The ends of the piston rods are secured in the spiders 30 and 31, and the bores thereof communicate with ports 111, as shown more clearly in Figs. 6 and 10. In order to control 70 admission of fluid pressure and exhaust from

the cylinder, we provide blowhead devices which are moved against the faces of the spiders into sealing engagement therewith, and effect registry with the ports 111. These blowheads are mounted on the bearing standards 28 and 29. 5 Similar blowheads are also carried by the bearing standards 28 and 29, in order to effect retractive movements of the work holders after they have been advanced on their guide rods, such retractive movements taking place at a point which is 10 diametrically opposite to the grinding station. Each of these blowheads is similar in construction and comprises a cylinder 112 which is suitably secured to the bearing standards. The cylinder is provided with a stem portion 113 for supporting a piston rod 114, the piston rod extending through both ends of the cylinder. On its inner end, the piston rod carries a bushing 115 of yieldable material, such as rubber or the like. A piston 116 carried by the piston rod 114, 15 is contained within cylinder 112, and serves to move the piston rod inwardly toward one face of the adjacent spider. This movement is effected by the admission of fluid pressure through pipe 117, a spring 118 serving to retract the piston rod when the fluid pressure is released. At its outer end, the piston rod 114 is extended through a suitable packing gland and nut 119, and carries a valve 120. The rod 114 is bored out 20 longitudinally, so as to permit passage of fluid 25 pressure therethrough, the sealing member 115 having a passageway therethrough, communicating with such bore.

When fluid pressure is admitted to the pipe 117, the piston and piston rod move inwardly 30 against the tension of the spring 118, thereby moving the sealing member 115 into sealing engagement with the face of the adjacent spider and effecting a continuous passageway for fluid pressure to the piston rod 59. Such fluid pressure 35 is admitted through a pipe 121, through control valve 120, and the passageway through the rod 114, the sealing member 115, and the port 111. When the pressure is removed from the pipe 117, the spring 118 causes the piston rod of the sealing member to be moved away from the face of the spider, thereby permitting successive indexing movement thereof.

45 It will be seen that one of the blowheads is moved into engagement with its associated spider 50 to permit admittance of fluid pressure to the cylinder 58, while the blowhead at the opposite end of the same piston rod, associated with the cylinder 58, moves into engagement with its 55 associated spider, to control exhaust from the cylinder 58. By means of adjustment of the valve 120, the speed of movement of the work holder is regulated by controlling the rate of exhaust from the cylinder 58. Therefore, the time to which a blank is subjected to a grinding operation 60 is controllable as desired.

During movement of the work holder to move a blank radially of a grinding element, we provide means for causing the clamp block 52 and the blank carried thereby, to be oscillated relative 65 to the face of the grinding element. This mechanism, as shown more clearly in Figs. 1, 5, 11, 12 and 13, comprises a rock shaft 125 which is journaled at one end in the upright 100 and adjacent to its other end in an upright 126. A crank 127 70 is secured to one end of the rock shaft 125, and a connecting rod 128 is connected to an eccentric 129, the eccentric being mounted on a shaft 130, which is driven by a motor 131, through reduction gear or speed change device 132. The rock 75

shaft 125 is provided with a radially extended portion 133, to which is secured at its upper and lower sides, plates 134 and 135, forming thereby an extended slotted member. The heretofore mentioned lever 57 secured to the end of the work holder block 48 is moved into position adjacent to one end of the slotted oscillating member, when the work holder is moved into grinding position. During traveling movement of the work holder on the rods 32, the end of the lever 57 moves into position between the plates 134 and 135, such plates being flared at their forward ends to facilitate entrance of the lever therebetween, while the shaft 125 is being oscillated. Thus rocking movement throughout a predetermined portion of traveling movement of the work holders on the rods 32 is imparted to the work holder.

The degree of oscillation or the extent of rocking movement imparted to the work holder is controlled by adjustment of the point of connection of the connecting rod 128 with the crank arm 127. The crank arm 127 slidably carries a block 136, as shown more clearly in Figs. 5 and 12, which is movable longitudinally of the crank arm, to various positions therealong. The block 136 is provided with a trunnion 137, to which the upper end of the connecting rod 128 is connected. The block 136 has threaded connection with a screw rod 138 which is suitably journaled in end plates carried by the crank arm. Through rotation of the screw rod 138, the crank throw may be readily adjusted to obtain the desired degree of oscillatory movement of the work holders, through the heretofore-described connection.

Near the end of the movement of the work holders on the rods 32, the lever 57 moves out of engagement with the plates 134 and 135, the grinding operation on a blank carried thereby, being then completed. A push rod 140 is slidably mounted in the bracket 126 in position to be engaged by the lever 57 after it has moved out of engagement with the oscillating device. The push rod 140 engages one end of a bell crank lever 141 which is pivotally mounted at 142 on the bracket 126, the other leg 143 of the bell crank lever having secured thereto a cable 144, the cable being moved through movement of the bell crank lever 141 for a purpose to be herein-after described. The bell crank lever is normally maintained in a central position with the push rod in projected position, by means of springs 145.

We have found it desirable to utilize fluid pressure to actuate the various moving parts of the machine, and in order to effect operation thereof in proper sequence, we provide timing mechanism for controlling the admission and exhaust of fluid pressure to the motivating devices heretofore described. The timer, as shown more clearly in Figs. 14, 15 and 16, comprises a casing 150, in which is disposed a shaft 151 mounted in suitable bearings in an end plate 152 and an end housing 153. A series of cams 154 are mounted on the shaft 151. Each cam engages the stem 65 of a valve 155, which is carried in a valve housing 156.

As shown more clearly in Figs. 18, 19 and 20, each valve body is provided with a pair of valves 155. One of the valves controls the flow of fluid pressure from an inlet port 157 to an outlet port 158, formed in the valve body. The other valve 70 155 controls exhaust of fluid pressure from the port 158 to an exhaust port 159. The valves 155 are of the poppet type and are normally held 75 on their seats by means of springs 160.

The timer is driven from the sprocket wheel 161 which is mounted on the shaft 130 of the speed reducer 132. A driving chain 162 passes around the sprocket 161 and around a sprocket wheel 163 that is mounted on one end of a shaft 164, the shaft 164 being journaled in the end plate 152 and the end housing 153. On its inner end, the shaft 164 carries a pinion 165 meshing with a gear wheel 166, which is suitably secured to the hub 167 of a clutch element 168, the clutch 168 being supported by bearings 169 in the housing 153. The face of the clutch element 168 is provided with notches or recesses for the entry of a clutch dog 170, which is carried by a wheel element 171, that is secured to the shaft 151. The clutch dog 170 is slidably mounted in the wheel element 171 for movement in directions axially of the wheel element into a notch in the clutch element 168. The clutch dog is yieldably urged in clutch engaging position by 20 means of springs 172. The clutch wheel 171 is provided with an annular groove or channel 173 and the forward end of a lever 174 rides within this groove. The other end of the lever 174 is pivotally mounted at 175 to the housing 150. 25

Spring 176 serves to yieldably urge the lever 174 toward the axis of the wheel 171. The forward end of the lever 174 is provided with a cam nose portion 177, which lies in the path of and cooperates with an inclined surface 178 (Fig. 16), 30 of a slot in the upper side of the clutch dog 170, to cause withdrawal or retraction of the clutch dog from a notch in the clutch element 168 at the completion of each revolution of the shaft 151 and the clutch wheel 171. 35

It will thus be seen that when the clutch dog 170 is released by lifting movement of the lever 174, it moves into engagement with one of the notches in the disc 168, and thereby completes the driving connection between the clutch element 168 and the clutch wheel 171, and thereby drives the cam shaft 151. As the cam shaft and the clutch wheel 171 approach the end of a single revolution thereof, the cooperating camming surfaces 177 and 178 cause withdrawal of the 45 clutch dog 170, thereby breaking the driving connection for the cam shaft.

As heretofore described, the bell crank lever 141 is actuated when the work holder reaches the end of its movement on the rods 32 and the cable 144 moved thereby. The cable passes over a sheave 180, mounted on the timer housing 150, and is secured at its end to the forward end of the lever 174. The lever 174 is thus raised to its dotted line position, as shown in Fig. 15, permitting the clutch dog 170 to move into one of the notches of the clutch element 168, thereby initiating another cycle of operations. A stop screw 181 limits upward movement of the lever 174 and prevents its movement out of the annular groove 173. During each complete revolution of the cam shaft, the cams 154 carried thereby cause actuation of the valves 155 in predetermined sequence, and thereby time the operation of the grinding machine, the sequence of operation and the timing periods for the various cams being graphically illustrated in Fig. 21.

Referring now to Figs. 21 and 22, fluid pressure from a suitable source, not shown, is admitted past a valve 200 and is directed through pipes 70 201 to the inlet port 157 of each of the valve bodies 156, associated with the timer mechanism. With the parts in the position as shown in Fig. 2, and with the motor 131 in operation, the carriage control lever 174 may be manually tripped 75

to cause the clutch dog 170 to move into driving engagement with the clutch element 168, thereby causing the cam shaft 151 to be operated. As shown in Fig. 21, the cams which control admission of fluid pressure from the pressure line 201 to the various cylinders, are shown in full lines, while the cams that control the exhaust from the said cylinders are shown in dotted lines. The cam 154a actuates its valve 155, 10 thereby permitting fluid pressure flow past the valve from the inlet 157 to the outlet 158. The outlet 158 is connected with the pipe 72 leading from the indexing cylinder 70.

The cam 154b permits closure of its associated valve 155 to prevent exhaust of fluid pressure through the exhaust port 159. The fluid pressure admitted to the cylinder 70 causes the piston contained therein to move to the left, thereby moving the indexing mechanism into its dotted line 20 position, as shown in Fig. 5. It will be seen that the roller 82 on the forward end of the piston rod 69 during retractive movement of the piston, engages the locking lever 65 and moves it into its dotted line position, thereby withdrawing the 25 locking dog 66 out of a notch in the notched plate 64, thus releasing the carriage.

Movement of the lever 65 out of locking position results in disengagement thereof with the crank lever 86, thereby permitting the valves 88 30 and 89 to close. Fluid pressure is admitted to the valves 88 and 89 through a pipe 203. The valve 88 controls flow of fluid pressure to the blowhead cylinders 112, so that when this valve is open, the pressure is admitted to the cylinders to cause 35 the piston rods 114 thereof to move the discs 115 into sealing engagement with the adjacent spider members 30 and 31, and establish a closed conduit to the cylinder 58. The valve 89 controls flow of fluid pressure through pipes 204 connecting with 40 certain of the pipes 121 of the blowheads.

With lever 65 in its retracted or release position, it engages the stem of a valve 205 which is mounted in a valve body 206 and suitably secured to the housing 28. The valve 205 serves to control exhaust of fluid pressure from the blowhead cylinders 112, the pipes or conduits 117 thereof being connected to a port in the valve body 206, located at one side of the valve 205. At the opposite side of the valve 205, the valve body is 50 provided with an exhaust port 208. It will be seen, therefore, that with the valve 205 open, the residual pressure in the cylinders 112 is exhausted to the atmosphere, thereby permitting the springs 118 to move the sealing discs 115 away from the spiders. Following these operations, cam 154c 55 actuates its valve 155 and admits fluid pressure to the pipe 71 leading to the opposite side of indexing cylinder 70. The piston therein is actuated, the pawl 67 engaging a tooth of the ratchet wheel 63, and causing advancing movement of the carriage. The carriage is thereby moved from its 60 position shown in Fig. 2 toward the blank feeding position. However, before the carriage reaches the feeding position, the cam 154d opens its valve 65 65 and admits fluid pressure to a pipe 210 leading to the pipe 93 of the locking cylinder 91.

The pipe 210 also has connection with the pipe 107 of the feeding cylinder 106. The piston rod 90 is thereby moved into position to be engaged 70 by the projecting end of a rod 41 to stop the carriage in its blank receiving position, as heretofore described. The pressure admitted to the cylinder 106 causes movement of the slide plate 102, thereby feeding the lowermost blank 54 from 75 the magazine into position on the clamp bar or

block 52. During the feeding movement of the blank to the holder, the cam 154c permits its valve 155 to close, thereby preventing flow of fluid pressure to the indexing cylinder.

Upon completion of the blank feeding operation, the cam 154d permits closure of its valve 155, thereby preventing pressure flow to the feeding cylinder 106. Its associated cam 154e operates to open the exhaust port 159, thereby permitting the retraction of the piston in the feeder 10 cylinder and exhaust of air therefrom.

To effect retraction of the blank feeder and retraction of the locking rod 90 to unlock the carriage, cam 154f operates its valve to admit fluid pressure to its outlet 158, which in turn is 15 connected to the pipes 108 and 92. Substantially simultaneously with admission of this fluid pressure to cause unlocking of the carriage and retraction of the blank feeder, fluid pressure is again applied to the indexing cylinder 70 by the 20 cam 154c, the indexing mechanism being actuated to complete the indexing of the carriage.

As shown in Fig. 2, as soon as the carriage moves slightly away from its intermediate loading position, the trailing end of the clamp 55 25 disengages from the cam block 109 and thereby securely clamps the blank on the work holder. The blank feeding fingers will, of course, move away from the work holders quite rapidly, so that there is no danger of their being damaged 30 through movement of the carriage.

Prior to the completion of the carriage indexing movement, valve 154g admits flow of fluid pressure to the pipe 81 leading to the cylinder 78. The piston 77 therein is moved to cause the piston 35 rod 79 to engage the upper end of the locking lever 65 and yieldably urge the locking dog 66 into engagement with the face of the locking disc 64. When the next notch in the locking disc 64 is 40 brought into position adjacent the locking member 66, it will drop quickly into such notch and lock the carriage. This snap action of the locking member eliminates danger of over-running of the carriage past the grinding position.

Shortly thereafter, cam 154c permits closure of 45 its valve to remove pressure from the indexing cylinder, while its associated exhaust-controlling cam operates to exhaust pressure from the indexing cylinder to the atmosphere.

When the locking lever moves into locking position, it actuates the crank lever 86, thereby actuating the valves 88 and 89. The valve 88 is actuated slightly in advance of the valve 89. Through the connections heretofore described, the air pressure is admitted past the valve 88 to the blowhead cylinders 112, and air pressure is admitted past valve 89 to the bores in piston rods 114. Flow of fluid pressure is therefore effected through the ports 111 and through the piston rods 59, to one side of the piston 60 in the cylinder 60 55 58. The work holder which is in grinding position is thereby moved along its guide rods 32. At the opposite side of the carriage, the previously-moved work holder will be moved along its guide rods and returned to its normal position. 65

Pressure is applied to the blowhead cylinders and flows through such blowheads to actuate the work holders, so long as the locking lever 65 is maintained in its locked position. As the timer approaches the end of its cycle of movement, cam 70 154a actuates its valve to admit fluid pressure through the pipe 72, and thereby causes the indexing piston to move in a retractive direction. However, before the indexing mechanism is fully retracted, the air pressure is removed through 75

closure of the valve associated with the cam 154a, so that at this time the locking lever is not moved out of carriage-locking position. The indexing mechanism is merely so positioned that upon completion of the grinding operation it may be fully retracted to cause quick actuation of the locking lever and consequent closure of the valves 88 and 89, to remove pressure from the blowheads and the work holder actuating pistons.

10 After partial retraction of the indexing mechanism, as above described, the camming surface 178 of the clutch dog 170 engages the cam surface of the lever 177, and the clutch dog is caused to move out of driving engagement with the 15 clutch element 168.

At this time the timing mechanism is thereby declutched from its driving mechanism, after making one complete revolution, and is not re-actuated until the work holder moves along the 20 guide rods 32, and actuates the trip lever 141 through engagement with the push rod 140. When the trip lever is actuated, the cable 144 lifts the lever 174, thereby releasing the clutch dog 170 and causing succeeding cycles of operations.

25 The speed at which the work holder is moved along the guide rods 32, is controlled by controlling the exhaust of air from the one side of the cylinder 59. This control of the exhaust flow is effected by means of the valve 120 on the outer 30 end of the piston rod 114. By adjustment of the valve 120, the rate of travel of the work holder may be regulated as desired. This is an important feature of our invention since for certain types of articles or blanks, it may be desirable 35 to subject the blanks to a longer or shorter grinding period. For example, with relatively thick blanks where a large amount of stock is to be removed, it is desirable to provide a greater time for removing such stock to prevent burning of the 40 metal and rapid wear on the grinding element, than when only a small amount of stock is to be removed from a blank.

Another important feature of our invention resides in the provision of oscillating the blanks 45 during grinding operation thereon, in order to form blanks with convex sides. Also, as shown in Figs. 12 and 13, not only may the degree or amplitude of oscillation imparted to the blank holder be adjusted through shifting of the point 50 of connection of the connecting rod 128 with the crank arm 127, but the angle of oscillation relative to the face of the grinding wheel may be adjusted through lengthening or shortening of the connecting rod 128, which may readily be effected by means of the adjusting nut 215. For 55 example, when the connecting rod 128 is shortened so that the line *a* (Fig. 13) indicates the center of oscillatory movement, the work holder and the blank carried thereby will be moved and 60 oscillated in an angular position relative to the face of the grinding wheel. This results in forming only the lower portion of the blank with a convex surface, whereby greater strength may be retained in the blank by non-removal of a too 65 great amount of material when sharpening the lower edge of the blank.

In some instances, when it is desired to grind the blank with flat sides, we hold the oscillating mechanism against oscillation so as to maintain 70 the face of the blank at any predetermined angular position relative to the grinding wheel. This is effected by merely removing the lower end of the connecting rod 128 from the eccentric 129 and positioning it on a stud 216 secured to the 75 bracket 126.

It will be seen that in the operation of the apparatus, the timing device is intermittently set in motion to effect a cycle of operations. Thus, when the timer has reached a position at which a knife holder with its knife is to be moved across the face of the grinding wheel, the timer comes to a stop and the rotatable carrier also is locked in a stationary position by the locking lever 65. At the completion of the travel of a knife holder across the grinding wheel, it will engage the push 10 rod 140 to operate the bell crank lever 41 and thereby again set the timer in operation to release the carrier and cause movement thereof to work-receiving position as indicated in Fig. 2, the carrier being held at that position by a stop 90. 15 Continued movement of the timer causes a blank to be fed to the holder, the stop 90 to be released and the carrier movement continued to bring another holder into grinding position, at which position the carrier is again locked by the latch 20 bar 65. During movement of each holder in carrying a blank across the grinding wheel, the previously-advanced holder from which a ground blank has been discharged is retracted axially of the carrier so as to be in position to receive another blank when it reaches the charging station. 25 Each time that a blank holder has completed its travel across the face of the grinding wheel, the timer is thereby set in motion for another cycle of operations.

We claim as our invention:

1. A grinding apparatus comprising a rotatable grinding wheel, work holders, a carrier movably supporting said holders and rotatable to bring the work holders successively into operative position 35 with respect to the grinding wheel, means for rotating the carrier intermittently, means operative in predetermined relation to movement of the carrier for shifting each work holder longitudinally of the carrier while such holder is in grinding position and while the carrier is stationary, and means operated by said movement of the work holder for controlling said intermittent movement of the carrier.

2. A grinding apparatus comprising a rotatable grinding wheel, work holders, a carrier movably supporting said holders and rotatable to bring the work holders successively into operative position with respect to the grinding wheel, means for rotating the carrier intermittently, means operative in predetermined relation to movement of the carrier for shifting each work holder longitudinally of the carrier while such holder is in grinding position and while the carrier is stationary, means operated by said movement of the work holder for controlling said intermittent movement of the carrier, and means for varying the rate of said longitudinal movement of the work holder.

3. A grinding apparatus comprising a rotatable grinding wheel, work holders, a carrier movably supporting said holders and rotatable to bring the work holders successively into operative position with respect to the grinding wheel, means for rotating the carrier intermittently, 65 means operative in predetermined relation to movement of the carrier for shifting each work holder longitudinally of the carrier while such holder is in grinding position, means for oscillating the work holder during said movement thereof, and means operated by said movement of the work holder for controlling said intermittent movement of the carrier.

4. A grinding apparatus comprising a rotatable grinding wheel, work holders, a carrier mov- 75

- ably supporting said holders and rotatable to bring the work holders successively into operative position with respect to the grinding wheel, means for rotating the carrier intermittently, 5 means operative in predetermined relation to movement of the carrier for shifting each work holder longitudinally of the carrier while such holder is in grinding position, means for supporting the work holder for pivotal movement on 10 the carrier during said longitudinal travel thereof, and means mounted independently of the carrier for oscillating the work holder about its pivot during said longitudinal movement.
5. A grinding apparatus comprising a rotatable grinding wheel, a carrier, means for intermittently rotating the carrier, a plurality of work holders disposed circumferentially of the carrier and movable axially thereon across the face of the grinding wheel while the carrier is stationary, 15 a timing device controlling the operation of the carrier-moving means and the work holder-moving means, and means actuated by movement of the work holder for controlling the operation of the timing device.
- 20 6. A grinding apparatus comprising a rotatable grinding wheel, a carrier, means for intermittently rotating the carrier, a plurality of work holders disposed circumferentially of the carrier and movable axially thereon across the 25 face of the grinding wheel while the carrier is stationary, a timing device controlling the operation of the carrier-moving means and the work holder-moving means, means actuated by movement of the work holder for controlling the operation of the timer, and means for varying the rate of movement of the work holder.
- 30 7. A grinding apparatus comprising a rotatable grinding wheel, a carrier, means for imparting rotative movements to the carrier, work 35 holders disposed circumferentially of the carrier, fluid pressure means for moving the work holders relative to and axially of the carrier and across the face of the grinding wheel, a locking device for holding the carrier against rotation 40 during grinding operations, means operable in timed relation to the carrier-moving means for actuating said locking device, and means actuated by locking movement of the locking device, for admitting fluid pressure to the said fluid 45 pressure actuating means for the work holder.
- 45 8. A grinding apparatus comprising a rotatable grinding wheel, a carrier, means for imparting rotative movements to the carrier, work holders disposed circumferentially of the carrier, 50 fluid pressure means for moving the work holders relative to and axially of the carrier and across the face of the grinding wheel, a locking device for holding the carrier against rotation during grinding operations, means operable in timed 55 relation to the carrier-moving means for actuating said locking device, means actuated by locking movement of the locking device for admitting fluid pressure to the said fluid pressure actuating means for the work holder, and means 60 controlled by said movement of the work holder, for effecting release of the locking device and rotative movement of the carrier.
- 65 9. A grinding apparatus comprising a rotatable grinding wheel, a rotatable carrier, a plurality of work holders disposed circumferentially of the carrier, piston and cylinder devices on the carrier for reciprocating work holders axially of the carrier, and provided with ports at each end of the carrier, a blowhead at one end of the 70 carrier positioned to register with the adjacent port of each piston and cylinder device when the associated work holder reaches grinding position, a blowhead device at the other end of the carrier positioned to register with the adjacent ends of the ports successively as the work holders pass from grinding position, a locking lever for holding the carrier in position during each grinding movement of the work holders, means for moving the lever into and out of locking position, means actuated by the lever when moved to locking position for moving the blowheads into cooperative relation with said ports, and other means controlled by locking movement of said lever for admitting fluid pressure through said blowheads to the said piston and cylinder devices.
- 75 10. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between the said device and the rocking member, relative to the axis of the rocking member and relative to said member's connection with the work holder.
- 15 11. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, and an eccentric device connected to said member, for rocking the member, to oscillate the work holder, the connection between the said rocking member and the eccentric device being adjustable in length, to change the angular path 20 of movement of the work holder.
- 20 12. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member and the work holder, means for shifting the point of connection between the device and the rocking member relative to the axis of the rocking member, and means for changing the angular path of movement of the work holder.
- 25 13. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 30 14. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 35 15. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 40 16. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 45 17. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 50 18. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 55 19. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 60 20. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 65 21. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 70 22. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.
- 75 23. The combination with a rotatable grinding wheel, of a work holder mounted for oscillatory movement, means for moving the work holder across the face of the grinding wheel, a rocking member mounted on an axis stationary relative to the work holder and having connection with said work holder during said movement, a device connected to said member, for rocking the member, to oscillate the work holder, and means for shifting the point of connection between said device and the rocking member, relative to the axis of the rocking member.

ber, to oscillate the work holder, and means for shifting the point of connection between said device and the rocking member, in a direction parallel to the face of the grinding wheel.

- 5 15. The combination with a rotatable grinding wheel, of a work holder mounted for oscillatory movement, means for moving the work holder across the face of the grinding wheel, a rocking member mounted on an axis stationary relative
10 to the work holder and having connection with said work holder during said movement, a de-

vice connected to said member, for rocking the member, to oscillate the work holder, means for shifting the point of connection between said device and the rocking member, relative to the axis of the rocking member, and means for oscillating the work holder about an axis perpendicular to the axis of its first-named oscillatory movement. 5
